ALUMINUM-ZINC-MAGNESIUM ALLOY

Albert Jager, Rome, N.Y., assignor to Revere Copper and Brass Incorporated, New York, N.Y., a corporation of Maryland

No Drawing. Filed Apr. 26, 1966, Ser. No. 552,363
3 Claims. (Cl. 75—146)

This invention relates to aluminum-base alloys and, more particularly, to an aluminum-zinc-magnesium alloy of improved extrudability and utility.

Extrudable free machining alloys, which are particularly useful as machine screw stock, are presently available in three different aluminum-base systems, to wit, aluminum-copper, aluminum-copper-magnesium and aluminum-magnesium-silicon. The machinability of each of these alloys is further improved by the addition of a small amount of lead or bismuth, or both. However, it is a characteristic of each of these alloy systems that air quenching at emergence from the extrusion dies does not develop optimum tensile strength, and accordingly rod extruded from these alloys, when it is to be used as machine screw stock, must be solution heat treated to develop its tensile strength.

An aluminum-base alloy system consisting essentially of aluminum, zinc and magnesium has been developed heretofore but has not exhibited suitable extrudability and machinability to justify its use as machine screw stock or the like. However, I have now discovered that when the zinc and magnesium contents of this system are maintained within relatively close limits, to wit, about 2% to 5.5% zinc and about 0.25% to 2.5% magnesium, the extrudability and utility of this aluminum base alloy system is unexpectedly improved by the addition of about 0.3% to 2.5% of lead or bismuth, or both.

Lead and bismuth are known aids for improving the machinability of various alloy systems, and they perform similarly in the system 2-5.5% zinc, 0.25-2.5% magnesium, balance essentially aluminum. However, both lead and bismuth, alone or in admixture and in total

die container temperature was 800° F. The extrusion was quenched by an air blast at the die, and the extrusion ram speed was held at 33 feet/minute.

TABLE I

Alloy	1	2	3	4
Nominal Composition, percent by Wt.:				
Zn	3.55	3.55	4.05	4.05
Mg	0.95	0.95	1.25	1.25
Pb	0.50	0.50	0.50	0.50
Bi	0.50	0.50	0.50	0.50
Al	Bal.	Bal.	Bal.	Bal.
Breaking Pressure, Tons/Sq. Inch at—				
825° F.	420	400	470	450
875° F.	380	360	415	400

By comparing the breaking pressure for Alloy 1 with Alloy 2, and for Alloy 3 with Alloy 4, it will be seen that the addition of lead and bismuth improved extrudability of the base alloy at any specified billet temperature.

The improved utility of the alloys of the present invention is shown by the data in Tables II, III and IV wherein certain properties of my aluminum-zinc-magnesium alloy are compared with those of the aforementioned prior art alloys based on the aluminum-copper and aluminum-magnesium-silicon systems. The aluminum-zinc-magnesium alloy representative of the invention contained 3.8% zinc, 1.1% magnesium, 0.5% lead, 0.5% bismuth, and the balance aluminum except for less than 1% impurities consisting primarily of iron and silicon. The prior art aluminum-copper alloy contained 5.5% copper, 0.5% lead and 0.5% bismuth, balance essentially aluminum, and the prior art aluminum-magnesium-silicon alloy contained 1.0% magnesium, 0.64% silicon, 0.5% bismuth, 0.25% copper, 0.10% chromium, balance aluminum. Each of these alloys was hot extruded at about 850° F. When indicated to be quenched at the extrusion die, they were quenched by a blast of compressed air at ambient temperature; when indicated to be solution heat treated, they were furnace heated to about 950° F. and then water quenched. Following the specified treatment, each extruded alloy was naturally aged at ambient temperature for 4 days.

TABLE II

Property	Condition	Al-Mg-Zn Alloy	Al-Cu Alloy	Al-Mg-Si Alloy
U.T.S. (K.s.i.)	[Quenched at die, naturally aged].....	44.8	33.9	25.1
	[Solution heat treated, naturally aged].....	46.1	44.5	34.0
Y.S. (K.s.i.)	[Quenched at die, naturally aged].....	27.9	23.9	21.8
	[Solution heat treated, naturally aged].....	32.1	32.7	27.6
Elong. (percent)	[Quenched at die, naturally aged].....	20.0	18.0	20.0
	[Solution heat treated, naturally aged].....	20.2	18.0	21.8
R. of A. (percent)	[Quenched at die, naturally aged].....	48.2	46.0	58.6
	[Solution heat treated, naturally aged].....	52.0	45	58.4

amount of between 0.3% and 2.5%, also improve the extrudability of the base alloy as can be seen from Table I. In this table, extrudability is indicated by the breaking pressure required to initiate extrusion at a specified billet temperature, lower breaking pressure representing better extrudability. Each of the alloys contained less than 1% impurities consisting primarily of iron and silicon. In each instance bookmold billets of the alloys 3 1/4 inches in diameter were homogenized by holding them at 815-865° F. for about 12 hours. After cutting each billet to an 11 inch length, one billet of each composition was extruded at each of two temperature levels (825° F. and 875° F.) to 1/16 inch rod. The preheat time for each extrusion was 2 hours at temperature and the

From the data of Table II it is apparent that the alloy of the invention attained substantially its ultimate tensile strength (U.T.S.), yield strength (Y.S.), elongation and reduction of area (R. of A.) merely by air quenching at the extrusion die, whereas both of the prior art alloy systems required solution heat treatment to develop these properties to comparable levels. A solution heat treatment is not required by the alloys of the invention because of their lower critical cooling rate compared to those of the prior art alloys.

The alloys referred to in Table II were similarly compared under the same conditions except for the addition of a 21% cold drawing operation after extrusion. Here again it will be seen from the resulting data reported in

Table III that the alloy of the invention attained its ultimate tensile strength and ductility without the solution heat treatment required by the other alloys.

TABLE III

Property	Condition	Al-Mg-Zn Alloy	Al-Cu Alloy	Al-Mg-Si Alloy
U.T.S. (K s.i.)	[Quenched at die and 21% drawn] [Solution heat treated and 21% drawn]	48.1 45.1	39.6 49.4	28.1 36.8
Y.S. (K s.i.)	[Quenched at die and 21% drawn] [Solution heat treated and 21% drawn]	41.3 37.8	34.1 42.9	26.4 33.1
Elong. (percent)	[Quenched at die and 21% drawn] [Solution heat treated and 21% drawn]	14.3 14.8	9.2 9.2	13.0 13.0
R. of A. (percent)	[Quenched at die and 21% drawn] [Solution heat treated and 21% drawn]	58.0 55.4	38.4 36.3	58.6 54.8

The ease of extrudability of the alloy of the invention compares favorably with or exceeds that of the aforementioned prior art alloys as demonstrated by the breaking pressure data reported in Table IV. For each alloy there is given the average value of a number of tests for the breaking pressure required to initiate extrusion. From this data it can be seen that the alloy of the invention had a better extrudability than the prior art aluminum-copper alloy and was comparable with the prior art aluminum-magnesium-silicon alloy. Thus, the alloy of the invention can be extruded at least as fast as the aluminum-magnesium-silicon system alloy and faster than the aluminum-copper system alloy.

TABLE IV

Alloy:	Average breaking pressure, tons/sq. inch
Al-Zn-Mg	380
Al-Cu	445
Al-Mg-Si	385

The higher extrusion speed of the alloys of the invention, as well as their ability to develop optimum tensile strength and ductility without solution heat treatment, make possible a significantly lower production cost. Their relatively low critical cooling rate also means that the alloys of the invention can be welded with the same weld metal with the expectation that the weld will age naturally to the parent metal characteristics. In addition, the alloys of the invention exhibit a better machined surface, a more uniform and brighter appearance when anodized, and better corrosion resistance, than the prior

art aluminum-copper and aluminum-magnesium-silicon system alloys.

The alloys of the invention advantageously have a

zinc content approximately four times that of their magnesium content. Increasing the zinc to magnesium ratio above 4:1 increases the precipitation hardening characteristics of the alloys, and decreasing this ratio increases their solid solution hardening characteristics. Up to about 1% by weight each of copper and manganese increases the strength of the alloys, and up to about 0.5% by weight of chromium serves as a grain growth inhibitor or refiner as well as to inhibit stress corrosion. Iron and silicon are generally indigenous impurities and can be tolerated up to a total of about 1% by weight with no significant effect upon the desirable and novel combination of properties of the alloys of the invention.

I claim:

1. An extrudable free machining aluminum base alloy consisting essentially of about 2 to 5.5% zinc, about 0.25 to 2.5% magnesium, about 0.3 to 2.5% bismuth or lead or both, and the balance aluminum.
2. An alloy according to claim 1 in which the ratio of zinc to magnesium contents is about 4:1.
3. An extrudable free machining aluminum base alloy consisting essentially of about 3.8% zinc, 1.1% magnesium, 0.5% lead, 0.5% bismuth, and the balance aluminum.

UNITED STATES PATENT OFFICE
CERTIFICATE OF CORRECTION

Patent No. 3,414,407

December 3, 1968

Albert Jager

It is certified that error appears in the above identified patent and that said Letters Patent are hereby corrected as shown below:

Column 2, line 29, "the" should read -- The --; line 31, after "silicon," insert -- 0.5% lead, --.

Signed and sealed this 17th day of March 1970.
